STRAIGHT BAR KNITTING MACHINE

Harry Wilfred Start, Carlton, and Ernest Start,
Wilford, EnglandApplication December 12, 1939, Serial No. 308,844
In Great Britain November 22, 1938

4 Claims. (Cl. 66—109)

This invention relates to improvements in straight-bar knitting machines of the "Cotton" type, in which the knocking-over bits in each division are carried on a bar which is disposed at the front of the needle-bar, and its object is to provide simple means whereby the knocking-over bar can be moved forward with the needle bar when the latter is disconnected from its presser cam lever in order to put it out of action.

10 The placing of the knocking-over bar in the front of the needle-bar is adopted in knitting machines which are adapted to knit tabs or the like at an intermediate point in a stocking or other garment, and which latter has to be run on the needles so that the first course of the tab can be knitted thereto. Whilst knitting this first course, a part of the garment has to be located at the back of the needle bar, and this can be readily effected when the knocking-over bar does not occupy the usual position at the back of the needle-bar.

15

According to this invention, provision is made whereby the knocking-over bar associated with each needle bar of the machine is coupled to and moved forward at the same time as the needle-bar, as is necessary when the needle-bar is disconnected from its presser cam lever in order to put it out of action.

This invention will now be more particularly described with reference to the accompanying drawings, in which

Fig. 1 is a sectional elevation, and

Fig. 2 is a front elevation of part of a straight bar knitting machine constructed according to our invention and

Fig. 3 is a detail plan of mechanism for withdrawing the knocking-over bar independently of the needle-bar.

Like letters indicate like parts throughout the drawings.

In carrying out this invention, the needle-bar is carried and actuated as usual by a system of cam actuated links and levers, which are according to the present invention arranged in the following manner.

Each needle-bar A provided in the machine is disposed on the upper ends of two arms B (only one of which is shown in the drawings) herein-after called needle-bar arms, which are connected by pins B¹ to the free end of arms C which are secured on a rocking shaft D disposed in bearings at the front of the machine. Secured on this front rocking shaft D is a dependent cam lever E, and its lower end is fitted with an anti-friction roller which bears on a cam on the main cam

shaft F, which is adapted to impart the required rising and falling movements to the needle-bar.

A dependent arm G is attached to the needle-bar, and the lower end of this arm is connected by means of a link G¹ to a dependent cam lever G² which is mounted on a separate shaft as shown, and the lower end of this cam lever G² is fitted with an anti-friction roller which bears on a presser cam on the main cam shaft F, which is adapted to impart the required pressing movements to the needle-bar.

The knocking-over bar H which is disposed in front of the needle-bar, is carried on two short arms H¹ (only one of which is shown) which are provided with adjustable fork-shaped ends H³ which engage with pins in the free ends of two arms H² on a rocking or auxiliary shaft J which is disposed in bearings at the rear of the needle-bar A. This rear rocking shaft J has a dependent cam lever J¹ secured thereto, and the lower end of this cam lever is fitted with an anti-friction roller which bears on a cam on the main cam shaft F, which is adapted to impart the required rising and falling movements to the knocking-over bar, and the to and away movements of the said bar relatively to the presser are effected by the following arrangement.

The upper ends of the knocking-over bar arms H¹ are connected by a link K to the upper end of an arm L secured on a second rocking or auxiliary shaft M disposed in the front of the knocking-over bar. The link K is pivoted at one end to the arm H¹ and its other end is provided with a fork K¹ which engages with a pin L¹ in the free end of the arm L, and is maintained in connection with the pin L¹ by a spring N connected between the arms H¹ and L.

Rocking motion is transmitted to the front shaft M by a bell crank lever M² pivoted loosely on the shaft M and provided with an anti-friction roller at one end which engages with a cam on the main shaft F whilst the other end is provided with a pin M¹ which engages with an arm O secured on the shaft M.

In order that the knocking-over bar may be moved forward with the needle-bar when the latter is moved forward out of action one or more abutments P are provided on the needle-bar and this abutment engages with corresponding abutments Q on the knocking-over bar when the needle bar is in its highest position as shown in Fig. 1 so that the knocking-over bar is moved forward with the needle-bar. When the needle-bar moves down into its knitting position the abutments P are below the abutments Q so that

the needle-bar is free to make the motions necessary for knitting a course.

With the arrangement described the needle-bar and knocking-over bar are moved forward together in order to run a fresh blank on the needles and that part at the front of the needles conveniently placed in position on the knocking-over bits before the latter and the needles are restored to their normal position.

- 10 In order that the knocking-over bar may be withdrawn independently of the needle-bar so that access may be had to the latter, a hand lever R is provided which is connected by a link S to the arm O previously described so that by 15 operating the hand lever R the shaft M can be angularly adjusted and the knocking-over bar withdrawn clear of the needle-bar. A catch may be provided in connection with the handle so that the knocking-over bar can be retained in its 20 withdrawn position.

What we claim as our invention is:

1. A straight bar knitting machine comprising in combination, a thread guide, a needle bar, a set of needles carried by said needle bar, sinkers, 25 a presser, means for operating the needles to cause them to knit, a knocking-over bar disposed in front of said needle bar, knocking-over bits carried by said knocking-over bar, a main shaft having cam means thereon, an auxiliary shaft 30 movable by the cam means on said main shaft, depending arms on said knocking-over bar and operated by connection with said auxiliary shaft for effecting raising and lowering of the knocking-over bar, a second auxiliary shaft movable 35 by the cam means on said main shaft, a link connected between said knocking-over bar and said second auxiliary shaft for moving the knocking-over bar toward and away from said presser, and at least one abutment on said needle bar engageable 40 with a corresponding abutment on said knocking-over bar for moving the said knocking-over bar forward when the needle bar is moved to its inoperative position.

2. A straight bar knitting machine comprising 45 in combination, a thread guide, a needle bar, a set of needles carried by said needle bar, sinkers, a presser, means for operating the needles to cause them to knit, a knocking-over bar disposed in front of said needle bar, knocking-over bits 50 carried by said knocking-over bar, a rocker shaft disposed in rear of said needle bar, an arm secured to said rocker shaft and having a pin at the free end thereof, a depending arm connected to said knocking-over bar and having a forked 55 end engaging said pin whereby to effect raising and lowering of the knocking-over bar upon movement of said rocker shaft, a second rocker shaft disposed in front of said needle bar, an arm secured to said second rocker shaft and having a pin at the free end thereof, a link having one 60 end connected to said knocking-over bar and having a fork at the opposite end thereof in engagement with the second said pin, spring means for holding the fork in engagement with the second 65 said pin whereby to effect movement of the knocking-over bar toward and away from said presser upon movement of said second rocker shaft, and at least one abutment on said needle bar engageable with a corresponding abutment

on said knocking-over bar for moving the knocking-over bar forward when the needle bar is in its highest position and is moved forward to its inoperative position.

3. A straight bar knitting machine comprising 5 in combination, a thread guide, a needle bar, a set of needles carried by said needle bar, sinkers, a presser, means for operating the needles to cause them to knit, a knocking-over bar disposed 10 in front of said needle bar, knocking-over bits 15 carried by said knocking-over bar, a rocker shaft disposed in rear of said needle bar, means connecting said rocker shaft to said knocking-over bar for effecting raising and lowering of the said knocking-over bar, a second rocker shaft disposed 20 in front of said needle bar, a link having one end connected to said knocking-over bar and having a fork at the opposite end thereof, an arm movable with said second rocker shaft and having a pin in one end thereof engageable with the 25 fork at the end of said link, a spring for maintaining the fork in engagement with said pin, a bell crank lever loosely mounted on said second 30 rocker shaft, a main shaft having cam means for operating the bell crank lever, a second arm secured to said second rocker shaft, a pin on said bell crank lever engageable with said second arm for effecting movement of the knocking-over bar 35 toward and away from said presser, and at least one abutment on said needle bar engageable with a corresponding abutment on said knocking-over bar for moving the knocking-over bar forward when the needle bar is in its highest position and is moved forward to its inoperative position.

4. A straight bar knitting machine comprising 35 in combination, a thread guide, a needle bar, a set of needles carried by said needle bar, sinkers, a presser, means for operating the needles to cause them to knit, a knocking-over bar disposed 40 in front of said needle bar, knocking-over bits carried by said knocking-over bar, a rocker shaft disposed in rear of said needle bar, means connecting said rocker shaft with said knocking-over bar for effecting the raising and lowering of the said knocking-over bar, a second rocker shaft 45 disposed in front of said needle bar, an arm secured to said second rocker shaft, a link having one end connected to said knocking-over bar and having the opposite end thereof in engagement with the end of said arm, a spring for maintaining the opposite end of said link in engagement with said arm, means for moving said second rocker shaft for effecting movement of said knocking-over bar toward and away from said presser, at least one abutment on said needle bar 50 engageable with a corresponding abutment on said knocking-over bar for moving the knocking-over bar forward when the needle bar is in its highest position and is moved forward to its inoperative position, a second arm secured to said second rocker shaft, a second link connected to said second arm, and a manually operated lever connected to said second link for moving the said second rocker shaft whereby to withdraw the knocking-over bar independently of the needle 55 bar.
